UNITED STATES PATENT OFFICE

112,625

DESIGN FOR A SHOE OR SIMILAR ARTICLE

Aleck E. Wagman, Dorchester, Mass.

Application October 27, 1938, Serial No. 80,712

Term of patent 3½ years

To all whom it may concern:

Be it known that I, Aleck E. Wagman, a citizen of the United States, residing at Dorchester, in the county of Suffolk and State of Massachusetts, have invented a new, original, and ornamental Design for a Shoe or Similar Article, of which the following is a specification, reference being had to the accompanying drawing, forming part thereof.

In the drawing,

Fig. 1 is a perspective view of a shoe or similar article showing my new design; and

Fig. 2 is a side perspective view of the disclosure in Fig. 1, the opposite side of the shoe having the same appearance as that shown.

I claim:

The ornamental design for a shoe or similar article, substantially as shown and described.

ALECK E. WAGMAN.
